UNITED STATES PATENT OFFICE.

WILLIAM M. HICKS, OF CRANFORD, NEW JERSEY, ASSIGNOR TO EDWARD D. HICKS
(TRADING AS WILLIAM S. HICKS' SONS), OF NEW YORK, N. Y.

PENCIL.

1,259,738.

Specification of Letters Patent. Patented Mar. 19, 1918.

Application filed August 23, 1917. Serial No. 187,819.

To all whom it may concern:

Be it known that I, WILLIAM M. HICKS, a citizen of the United States, residing at Cranford, in the county of Union and State of New Jersey, have invented certain new and useful Improvements in Pencils, of which the following is a specification.

My present invention pertains to an improved pencil, and the objects thereof are as follows:

First, to produce a pencil in which a relatively small lead may be employed which does away with the necessity of resharpening the same even though the protruding portion of the lead be broken off.

Second, to provide an impeller for the lead which has a relatively slow movement and by reason of which waste of lead is avoided.

Third, to provide means whereby the lead is supported by the point, and this by a tubing which is preferably made of the same material as the pencil case, as for instance, silver, thus avoiding corrosion of the tube and a consequent impedance of the feeding of the lead.

Fourth, the provision of a holder under the barrel cap for a rubber eraser.

Fifth, to so construct the barrel and the impelling mechanism for the lead that a large magazine or holder will be provided for the leads which is substantially co-extensive of the length of the pencil, and which magazine is normally closed by the eraser-holder just mentioned.

The pencil is shown in the annexed drawings, wherein:

Figure 1 is a longitudinal sectional view of the structure, the cap or cover for the eraser being in place;

Fig. 2 is a similar view of the barrel and the interiorly-threaded tubular member which co-acts with the lead-impeller, the eraser-holder being shown as unscrewed from the barrel proper, and the cap for the eraser being likewise omitted;

Fig. 3 is a longitudinal sectional view of the impeller and its guiding tube, together with the point portion of the pencil;

Fig. 4 is a side elevation of the impeller guiding-tube and the pencil point;

Fig. 5 is a perspective view of the lead-impeller;

Fig. 6 is a transverse sectional view taken

on the line VI—VI of Fig. 1 and upon an enlarged scale; and

Fig. 7 is a like view taken on the line VII—VII of Fig. 1.

In the drawings, 1 denotes the barrel in which is mounted an interiorly-threaded tubular member 2, said member at its upper end being secured or sweated into a second relatively short tubular member 3, which in turn is threaded or otherwise secured to a cross bar 4 (see more particularly Figs. 1 and 7), the ends of which bar are soldered to the interior of the barrel 1. As will be seen upon reference to Fig. 7, the bar 4 is narrow, and spaces 5 are left upon each side of the bar between it and the inner walls of the barrel. Said tubular member 3 extends through the bar and projects slightly beyond the end of the barrel 1, forming a threaded projection 6 to which is removably secured a tubular section 7, in the inner end of which is secured a threaded collar or sleeve 8 adapted to be screwed down upon the projection 6. The outer end of the member 6 may be closed by a disk 6a.

The member 7 and its attached collar 8 form a closure for the openings 5 when the parts are screwed together, and likewise provide a receptacle or holder for an eraser 9. Said member 7 is of a diameter slightly less than that of the barrel 1, and a cap-piece 10 is adapted to be slipped over this member and the eraser carried thereby, the lower or marginal end of said cap 10 forming a flush joint with the end of the barrel when the parts are brought to the position which they normally occupy, as in Fig. 1.

Mounted within the tubular member 2 and extending throughout the length thereof is a split tube or guiding element 11, the tube being provided with a collar 12 at its upper end which prevents the guiding element from being withdrawn from the tubular member, but yet permits relative rotation of the element with reference to said member. This tube 11 is adapted to receive the lead-impeller comprising a rod 13 adapted to make a close fit with the interior of the tube, and a cross bar 14 the ends of which project outwardly through the slots in said tube 11, and engage the threads formed upon the interior of the tube 2. The lower or outermost end of the tube 11 is not split,

and such unsplit portion is sweated or otherwise secured to a bushing 15, the lower end of which is tapered, and in turn secured to the conical-shaped pencil point 16. The member 11, moreover, may be secured to a cross plate or disk 17 mounted in the larger end of the element 16, and when the parts are assembled said element 16 abuts and makes a close fit with the lower end of the barrel 1.

10 The disk 17 thus forms a closure for the lower end of the barrel, which by reason of the construction above set forth, forms a relatively large magazine for the pencil leads. Said leads may be readily introduced 15 into the magazine through the openings 5 when the eraser-holder 7 is unscrewed from the threaded projecting element 6.

20 As above noted, it is designed to use relatively small leads, the magazine being capable of holding a large number of said leads of substantially the full length of the barrel. The leads are omitted from the drawing in so far as the magazine is concerned, 25 but a short section of lead denoted by 18 is indicated in Figs. 1, 3 and 4.

30 The element 16, the outer end of which is drawn down or so formed as to directly support the lead, the barrel 1, the tube 3 and its extension 6, the eraser-holder 7, the cap-piece 10, and the cross bar 4 will all preferably be formed of a precious or superior metal, as silver, so that the pencil will not corrode. This is of special advantage in the 35 element 16 for the reason that it facilitates the feeding out of the lead under the action of the impeller even though the lead be small, and this without breaking the lead. Where it is attempted to use a small lead 40 fed through a tube which is formed of a metal which will corrode, perspiration from

the hands of the user will frequently cause such corrosion as will impede the proper feeding of the lead or without exerting such force upon the lead where it is small, as to cause it to be broken or ruptured. 45

The action of the impeller is seemingly clear, as it is of the usual type. By holding the barrel and rotating the point 16 the impeller may be caused to move forward or backward according to the direction of rotation. The thread formed upon the interior of the tubular member 2 is of very slow pitch, so that the lead will be protruded but a short distance upon the complete 50 revolution of the barrel with reference to the point 16. 55

Having thus described my invention what I claim is:—

In a pencil, the combination of a barrel; 60 a pencil point relatively rotatable thereto, said point making a close fit with the outer end of the barrel; a disk carried by the point and closing the lower end of the barrel; a lead-impelling mechanism mounted within 65 the barrel and spaced from the inner walls thereof; a tubular member adapted to support said impelling mechanism at its upper end, said tubular member extending outwardly beyond the end of the barrel and being exteriorly threaded; a cross bar holding 70 said tubular member in place; a tubular eraser-holder having a threaded member adapted to be screwed upon the threaded extension of the tubular member aforesaid; 75 and a cap-piece fitting over said eraser-supporting member and making a close fit with the barrel.

In testimony whereof I have signed my name to this specification.

WILLIAM M. HICKS.
